[57] CLAIM

The ornamental design for a baseball counter-sorter, substantially as shown and described.

DESCRIPTION

FIG. 1 is a top and left front isometric view of a baseball counter-scorer showing my new design;
FIG. 2 is a top plan view thereof;
FIG. 3 is a bottom plan view thereof;
FIG. 4 is a left side elevational view thereof, the right side being a mirror image thereto;
FIG. 5 is a side elevational view thereof;
FIG. 6 is a rear side elevational view thereof.
